UNITED STATES PATENT OFFICE.

JOHN F. MAGNUSON, OF SAN JOSE, CALIFORNIA.

PATTERN TEMPLET.

Application filed April 13, 1922. Serial No. 552,259.

To all whom it may concern:

Be it known that I, JOHN F. MAGNUSON, a citizen of the United States, and resident of San Jose, in the county of Santa Clara and State of California, have invented certain new and useful Improvements in a Pattern Templet, of which the following is a specification.

It is the object of my invention to provide a templet for laying out a pattern for garments such as coats, vests, trousers, etc., and parts of garments such as sleeves, hoods or capes.

It is a particular object of my invention to provide a templet of the character indicated that may be extended for use in laying out patterns for garments of varying size, or which may be used directly in marking the cloth.

20 In the drawing:—

Figure 1 shows a plan view of the templet arranged to mark out a paper pattern of one portion of a coat.

Figure 2 is a plan view of the templet arranged to mark out a paper pattern of another portion of a coat.

Referring more particularly to the drawing I show at 1—2—3 three measures marked off in inches and fractions thereof and held in parallel relation to each other by means of a member 4 pivoted to strip 2 at 5. To each end of member 4 is a shorter member 6—7 pivotally connected thereto as well as to strips 1—3 at points 8—9 respectively as shown. The several pivotal points 5—8—9 all being spaced upon the central line of the measures 1—2—3 as shown.

40 Strips 1 and 3 have a groove or slot 10 and 11 both of equal length cut therein as shown. Said grooves being arranged upon opposite sides of the central points 8—9 and having members 12—13 slidably and pivotally mounted therein as shown. The central points of members 6—12 and 7—13 are pivotally connected at points 14—15 respectively as shown.

Strip 2 has two equally long grooves 16—17 spaced from the central point 5 in which are slidably and pivotally mounted members 18—19 having their outer ends pivotally connected at points 20—21 to the free ends of members 12—13 as shown. The central points of members 18—19 being pivotally connected to the member 4 at points 22—23 as shown. The length of all the

members 6—7—12—13—18—19 being equal to half the length of member 4, the whole going to make up a set of lazy tongs which hold strips 1—2—3 in parallel relation to each other at all times.

Pivotaly mounted upon one end of strip 3 is a fourth strip or measure 3^a which is graduated in inches and fractions thereof as shown.

Mounted upon strips 1 by tacks 28 are shown two cardboard patterns as 24—25, strip 2 having the pattern 26 while strip 3 has pattern 27 as shown. These patterns being held in place by the thumb tacks 28 stuck into the under surface of the wooden strips can be taken off and rearranged or others of different design placed thereon at will, the sizes and location of each depending upon the cut and size of the garment being marked out.

In using the pattern for marking out the outlines on paper of the front and side portion of one-half of a coat the paper is laid out as indicated in dotted lines at 29 and the pattern superimposed thereon.

The person to be fitted is first measured from the neck down the back to determine the length of the coat to be made. This length is measured off on the strip 2 and pattern element 26 secured in position as described with its lower end coinciding with the measurement obtained. Element 24 is now mounted on strip 1 and slightly advanced as to element 26, and element 25 positioned at its upper end. The measure of the chest is now taken and strips 1 and 3 spaced accordingly. For instance if the chest measurement is thirty-eight inches then the strips 1 and 3 are spaced fifteen inches apart.

It is only necessary to now mark around the outer edges of said members. Between points A—B a suitable lapel is marked in as shown in dotted lines, the portion C being laid off by moving the measure 3^a into the position 3^b indicated in dotted lines and the portion D being drawn in free hand. The portion E of the arm hole is also drawn in free hand as is also the portion F and G.

Another paper 30 is now placed in position and the pattern laid thereon with member 27 in the position shown and measures 2 and 3 spaced the proper distance by measure 3^a. Member 27 is now traced around to the point H where the line is continued on the proper curve to point I.

on the inner side of measure 2. Line J is now drawn in straight across to the inner edge of measure 3 and thence carried upward a distance and thence on a curve outwardly to a given point as K on the outer edge of measure 3 and thence to the point L.

5 Cloth cut to the two paper patterns described form one-half of a coat. It is clear of course that the extensible pattern may be 10 used directly on the cloth when desired and may be varied in detail for use in cutting out many different kinds of garments or parts of the same.

15 It is clear from the above disclosure that the device is highly efficient for the work for which it is designed, and that it obviates the necessity of using the square now commonly used by tailors in cutting out patterns and greatly reduces the time and labor of 20 doing that class of work.

It is to be understood, of course, that while I have herein shown and described one particular embodiment of my invention that changes in form and construction and 25 method of operation may be made within the scope of the appended claims.

I claim:—

1. A device of the character indicated including a pair of parallelly arranged 30 measures, an arm pivotally mounted at one end on each measure and pivotally connected at the other end to each other, an arm pivotally mounted at its central point to the center of each of said first mentioned 35 arms, each of said second mentioned arms being pivotally connected to each other at one end and slidably connected to one of said measures at its other end.

2. A device of the character indicated 40 comprising three parallelly arranged measures,

ures, an arm pivotally mounted at its center to the center measure, an arm pivotally mounted on each outer measure and to the adjacent end of said first arm, a pair of arms pivotally and slidably connected to 45 one outer measure and to the center measure and pivotally connected to each other at their inner ends, one of said arms being pivotally connected at its center to said first mentioned arm and the other of said arms being pivotally connected at its center to the adjacent second mentioned arm, and a second pair of arms directed oppositely to said first pair of arms and pivotally and 50 slidably connected to said center measure and the other outer measure and pivotally connected to each other at their inner ends, one of said last mentioned pair of arms being pivotally connected at its center to said first mentioned arm, and the other being pivotally connected at its center to the adjacent second arm.

3. A device of the character indicated including a central measure, a measure arranged on each side thereof in parallel relation thereto, two sets of lazy tongs mounted on said central measure to extend in opposite directions therefrom, one leg of each set being slidably mounted in said center measure, and one leg of each set being a unitary part of the corresponding leg of the other set and crossing said center measure and pivoted thereon, one outer leg of each set being pivotally mounted upon an outer measure, and the other outer leg of each set being pivotally and slidably mounted upon the adjacent outer measure whereby to maintain all the measures in parallel relation to each other.

JOHN F. MAGNUSON.
